HOUSING FOR BICYCLE LAMP

Anton J. Panzica, Hinsdale, Ill., assignor to Arnold, Schwinn & Co., Chicago, Ill., a corporation of Illinois

Filed Aug. 30, 1961, Ser. No. 66,555

Term of patent 14 years

(Cl. D48—24)

FIG. 1 is a perspective view of a housing for bicycle lamp showing my new design;

FIG. 2 is a side elevational view thereof; and

FIG. 3 is a rear elevational view thereof.

The dominant features of my design reside in the portion shown in full lines.

I claim:

The ornamental design for a housing for bicycle lamp, substantially as shown and described.
